JOHN LOVATT, OF TARRYTOWN, NEW YORK.

Letters Patent No. 75,938, dated March 24, 1868.

IMPROVEMENT IN MACHINE FOR WINDING BUTTON-HOLE TWIST, &c.

The Schedule referred to in these Letters Patent and making part of the same.

TO ALL WHOM IT MAY CONCERN:

Be it known that I, JOHN LOVATT, of Tarrytown, in the county of Westchester, and State of New York, have invented a new and improved Machine for Winding the Outside Layer or Layers of Button-Hole Twist, Silk, or other Fibrous Threads, in any desirable pattern; and I do hereby declare that the following is a full, clear, and exact description thereof, which will enable others skilled in the art to make and use the same, reference being had to the accompanying drawings, forming part of this specification.

The present invention relates to an improved machine for winding the outside layer or layers of button-hole twist, silk, or other fibrous thread on the spool, which is hung in any suitable manner, to revolve through a flier, that is arranged to revolve around the spool, but in an opposite direction thereto, and in a plane at any angle to the same, the flier and spool being arranged to revolve at suitable velocities, and the spool and velocities being susceptible of adjustment in accordance with the size of the thread, and the pattern to be wound. In the accompanying plate of drawings my improved machine is illustrated—

Figure 1 being an elevation of one side of the machine,

Figure 2 a plan or top view of the spool and flier, showing the relative positions, and

Figure 3 a view of the spool, with the outside layer wound upon it, in the machine embraced in the present invention.

Similar letters of reference indicate like parts.

A, in the drawings, represents the base or pedestal of the machine, to which is secured an upright, B, having a horizontal arm, C, fixed to and across its upper end. This arm C, at one end, D, is provided with an upright or post, E, in the upper end of which turns a horizontal spindle, F, carrying, at one end, a flier, G, which is there secured to it in any proper manner. H, a pulley, fixed to the opposite end of the spindle F to that which carries the flier, through which pulley the said spindle, and consequently the flier, are to be revolved in any suitable manner, by a connecting-belt or band, or the same result may be obtained by a system of gearing or otherwise. I, an upright arm, secured to the opposite side of the post B to that on which the flier is arranged, by means of a headed screw-bolt and nut, marked, in the drawings, J and K, or in any other suitable manner, so that the said arm can be swung around upon the post B, to stand at an angle more or less acute, with regard to the plane of movement of the flier, and be there secured, for a purpose to be hereinafter described.

In the upper end of the upright, I, a horizontal spindle, L, is arranged to turn, by connecting its pulley, M, through a belt, N, or by suitable gearing, to the driving-power employed, this spindle being provided for holding the spool on which the button-hole twist, silk, or other fibrous threads are wound, and the outer layer or layers of which are to be wound to the desired pattern.

In the use of the machine above described, the spool on which the button-hole twist, silk, or other fibrous thread is wound, and which is to have its outside layer or layers finished or wound to the desired pattern, is first placed and secured upon its spindle, L, with the twist, silk, or other fibrous thread passing therefrom through the eye of the outer end of the flier, and thence through the centre of the spindle to which such flier is fixed, that, for this purpose, is made hollow, or of a tube-shape, thence on to a self-acting drum, until enough of the material is unwound off the spool to complete the outer layer or layers.

The relative speeds at which the spool and the flier are to revolve are then adjusted, according to the size of the material being wound, and the pattern to be obtained, by means of cords and pulleys, when, adjusting the arm carrying the spool-spindle to the proper or desired angle with regard to the flier, they are then set in motion, revolving in opposite directions, whereby the required pattern or figure is produced on the outside layer or layers of the material being wound, the peculiarities in the appearance of which will depend upon the relative speeds of the flier and spool, as well, also, as their relative positions, produced by the adjustment of the arm carrying the spool-spindle.

To prevent the twist, which naturally forms at every turn of the flier, from passing on to the spool, I have arranged, at the mouth or end of the flier-spindle, where the material being wound enters, a parter, L², which forces the accumulating twist to the end of the material being wound, where it untwists in the hand of the operator, when detached from the holder and parter.

Having thus described my invention, what I claim as new, and desire to secure by Letters Patent, is—

1. The adjustable flier and holder, constructed and arranged to operate substantially as described.
2. I also claim the parter L², or its equivalent, combined and arranged with the flier, substantially as and for the purpose specified.

JOHN LOVATT.
